UNITED STATES PATENT OFFICE.

FREDERIC WILLIAM PANSE AND CHRISTIAN FREDERIC KLOTZ, OF NEW YORK, N. Y.

MACHINE FOR MAKING LOOPED TWISTED WIRE.

SPECIFICATION forming part of Letters Patent No. 320,582, dated June 23, 1885.

Application filed November 26, 1884. (No model.)

To all whom it may concern:

Be it known that we, FREDERIC WILLIAM PANSE and CHRISTIAN FREDERIC KLOTZ, subjects of the Emperor of Germany, and residents 5 of the city of New York, in the county and State of New York, have invented new and useful Improvements in Machines for Making Looped Twisted Wire, of which the following is a specification.

10 Our invention relates to improvements in machines for making looped twisted wire; and it consists, essentially, in the combination of the following devices, namely: a revolving spindle upon which two reels for the reception 15 of coils of wire are mounted, the wires passing through the perforated spindle and through diametrically-opposite holes in the spindle-head, so that on leaving the spindle-head the wires are revolved at a short distance from each other and from the axis of 20 the spindle; sliding carriages moving in proper ways attached to or forming part of the frame and provided with movable pins and means for alternately inserting said pins between the wires near the end of the spindle-head, and withdrawing them at the other end 25 of the throw of the carriages, so that the wires are twisted between the spindle-head and the pins receding from the same, while loops are 30 formed where the pins had been inserted; and, finally, delivery-press rolls.

In the annexed drawings, Figure 1 is a top view of our machine; Fig. 2, a longitudinal section, on a larger scale, of the sliding carriages and their supports, showing the end 35 of the spindle in elevation. Fig. 3 is a longitudinal section of the end of the spindle; Fig. 4, a transverse section of the sliding carriages and their ways. Fig. 5 shows the cam actuating the lever for depressing the pins for forming the loops, and Fig. 6 the cams for operating the sliding carriages.

Similar letters refer to similar parts throughout the several views.

45 A in Fig. 1 is the frame of the machine; B, the driving-shaft supported in bearings C and C'; D, a crank-wheel for revolving the shaft B.

E is the spindle, supported in bearings F and F'; G, a shaft resting in bearings H and H'.

50 Upon the shaft B are bevel-gears I and J,

meshing into bevel-wheels K and L on the shafts G and E. These bevel-wheels are all of the same size, so that the shafts B, E, and G revolve at the same speed.

M and N are reels pivoted on a forked bracket, O, mounted upon the outer end of the spindle E.

P and P' are the caps of roll-housings, of the ordinary construction, said housings forming part of the frame A, and containing the bearings for the upper and lower roll-shafts, Q, and Q'.

R is the upper roll, which is grooved for the reception of the twisted wires, the lower roll being grooved in the same manner. Set-screws passing through the caps P and P' bear upon springs on the top of the upper bearings, so that the pressure upon the rolls can be adjusted.

The shaft G has formed upon it a screw-thread, s, which meshes into a worm-wheel, W, upon the outer end of the lower roll-shaft, Q'. Spur-wheels S upon the opposite ends of the shafts of the rolls transmit motion from the lower to the upper roll. The shaft G is also provided with teeth t, meshing into a spur-wheel, T, supported in a standard, U, attached to the frame. The outer end of the shaft G carries a bevel-wheel, V, meshing into a larger bevel-wheel, X, upon a shaft, Y, supported in brackets Z and Z'.

a is a flanged plate attached to the two roll-housings; b, a plate on the top of the plate a.

c and d are sliding carriages moving in ways in the plates a and b, as shown in Figs. 2 and 4.

e and f are connecting-rods attached to the sliding carriages c and d. The outer ends of the rods e and f have slots, through which the shaft Y passes, and roller-pins g and h, against which cams i and j on the shaft Y act, so as to move the carriages c and d away from the spindle, the return motion being effected by springs K, Fig. 1. Upon the front of the wheel T is a cam, l l', for operating levers m and m'.

The arrangement of the sliding carriages c and d is shown in detail in Figs. 2 and 4. The lower side of the plate a and the upper side of the plate b are recessed, the recesses forming sliding ways for the carriages d and c. 100

The top of the plate *a* and the bottom of the plate *b* are on a level with the axis of the spindle and grooved in the line of the axis of the spindle, to allow the twisted wire to pass through, as shown in Figs. 2 and 4. The two sliding carriages are both alike, and formed with channels within which plates *o* and *o'* have vertical motion.

From the lower sides of the plates *o* and *o'* project studs *p* and *q* and *p'* and *q'*, supported on coiled springs, which allow the plates to be depressed, but throw them back when released. The outer ends of the studs *p* and *p'* form pins *r* and *r'*, which, when the plates *o* and *o'* are pressed against the bottoms of the channels project beyond the line of the axis of the spindle *E*.

The plates *a* and *b* are notched in the line of the path of the pins *r* and *r'*, as shown in the drawings, Figs. 2 and 4.

Upon the plates *o* and *o'* are staples *z* and *z'*, through which pass arms projecting from the ends of the levers *m* and *m'*, so as to allow the carriages to slide freely on said arms, which alternately impart to the plates *o* and *o'* the positions shown in Figs. 2 and 4.

Fig. 3 shows the end of the spindle *E* in section. This spindle *E* is perforated, so as to allow the two wires *v* and *w* to be passed through it and through holes in the projecting end *u* of the spindle, which holes are diametrically opposite.

The operation of the machine is as follows: Coils of wire are placed upon the reels *M* and *N*. The upper carriage, with the plate *b*, is removed, the lower carriage brought into the position shown in Fig. 2, and the rolls raised up. The ends of the wires *w* and *v* are passed through the spindle *E* and through the holes in the projecting end *u* of the same, then past the pin *r'*, as shown in Fig. 3. Beyond the pin *r'* the wires are twisted together for a few turns and the ends placed into the longitudinal central groove of the plate *a* and over the top of the lower roll, when all the parts are replaced into their proper positions. With some experience the wires may also be inserted without first removing any parts of the machine. By turning the crank in the proper direction—that is, downward from the position shown in Fig. 1—the wires are twisted between the pin *r'* and the projecting end *u* of the spindle *E*, the lower carriage, *d*, moves toward the rolls, while the wires are fed along by the rolls at the same speed, and the upper carriage is released from the cam *j* and brought forward by the spring *k*. When the lower carriage is at the end of its stroke, away from the spindle, the pin

r' is withdrawn through the action of the cam *l* *l'* and lever *m'*, while at the same time the upper pin, *r*, is inserted between the two wires in front of the spindle, after which the upper carriage moves toward the rollers, and so on. By thus alternately inserting the pins of the two carriages a twisted wire is formed with loops at equal distances. The finished wire is pressed and delivered by the delivery-rolls, and may be wound upon reels in the usual manner.

When the wires are not to be pressed the delivery-rolls may be omitted.

The necessary tension is maintained in the wires *v* and *w* by springs on the bolts, by which the reels *M* and *N* are attached to the bracket *O*, or by any other suitable means.

The distance between the loops can be changed by changing the speed of the wheel *T* and the length of the cams *i* and *j*.

What we claim as our invention in a machine for making looped twisted wire is—

1. The combination of a revolving spindle with reels for wire mounted thereon, two carriages secured in suitable ways and provided with movable pins, mechanism, substantially as described, for alternately inserting said pins between the wires and withdrawing them therefrom, and mechanism for actuating the moving parts, substantially as specified.

2. The combination of a revolving spindle with reels for wire mounted thereon, two carriages secured in suitable ways and provided with movable pins, mechanism, substantially as described, for alternately inserting said pins between the wires and withdrawing them therefrom, delivery-press rolls, and mechanism for actuating the moving parts, substantially as specified.

3. The combination of the revolving spindle *E* with its head *u*, reels *M* and *N*, mounted upon the spindle, ways *a* and *b*, sliding carriages *c* and *d*, shaft *Y*, with cams *i* and *j*, and connecting-rods *e* and *f*, for operating said carriages, pins *r* and *r'* within the sliding carriages, cam-wheel *T*, levers *m* and *m'*, for alternately inserting said pins between the wires and withdrawing them therefrom, and delivery press-rolls *R* and *R'*, substantially as specified.

In testimony that we claim the foregoing as our invention we have signed our names, in presence of two witnesses, this 24th day of November, 1884.

FREDERIC WILLIAM PANSE.
CHRISTIAN FREDERIC KLOTZ.
